GAS-FIRED UNIT HEATER OR SIMILAR ARTICLE

Nicholas R. Foloky and Edward A. Norman, Jr., Columbus, Ohio, assignors to Norman Products Company, Columbus, Ohio, a corporation of Ohio

Application October 10, 1956, Serial No. 43,291

Term of patent 7 years

(Cl. D81—10)

FIG. 1.

FIG. 2.

FIG. 3.

Fig. 1 is a side elevational view of a gas-fired unit heater or similar article, showing our new design;

Fig. 2 is a top plan view on a somewhat smaller scale; and

Fig. 3 is a bottom plan view thereof also on a smaller scale.

We claim:

The ornamental design for a gas-fired unit heater or similar article, substantially as shown.
